FIG. 2.

UNITED STATES PATENT OFFICE.

RAYMOND FISHER, OF PHILADELPHIA, PENNSYLVANIA, ASSIGNEE TO WILLIAM F. TAUBEL, INCORPORATED, OF RIVERSIDE, NEW JERSEY, A CORPORATION OF NEW JERSEY.

STRIPING ATTACHMENT FOR KNITTING MACHINES.

1,194,831.

Specification of Letters Patent. Patented Aug. 15, 1916.

Application filed April 27, 1915. Serial No. 24,322.

To all whom it may concern:

Be it known that I, RAYMOND FISHER, a citizen of the United States, residing in Philadelphia, Pennsylvania, have invented 5 certain Improvements in Striping Attachments for Knitting-Machines, of which the following is a specification.

My invention relates to certain improvements in a knitting machine of the type 10 shown in J. D. Hemphill's Patent No. 923,443, dated September 7, 1909, my invention relating to the devices whereby the knitting yarn is fed to the needles of the machine and comprising means whereby quick 15 changes of yarn can be effected for the purpose of producing relatively narrow stripes.

In the accompanying drawings—Figure 1 is an end view of sufficient of a knitting machine of the type to which my invention relates to properly illustrate those parts of the machine constituting the subject of my invention, and Fig. 2 is a view, partly in section and partly in elevation, looking in the direction of the arrow Fig. 1, and on a 25 larger scale than said figure.

In Fig. 2 of the drawing, 1 and 1^a represent two of the yarn feeders of a machine of the Hemphill type, these yarn feeders being normally moved by the action of springs 2 30 to the yarn feeding position shown at 1^a but being susceptible of elevation to the position shown at 1 in order to carry the yarn out of range of the needles.

The yarn feeders are under control of levers 3 and 3^a mounted upon the frame of the machine and each of these levers usually has a connection 4, 4^a with a pattern drum mounted upon the lower portion of the frame of the machine and so constructed 35 that when the yarn feeder 1 is raised the feeder 1^a will be lowered, and vice-versa, so as to provide for the feeding of either yarn to the needles, and, supposing the yarns to be of different colors, the consequent formation of stripes in the knitted web. The usual pattern mechanism, however, which acts upon the levers 3, 3^a through the medium of the connections 4, 4^a is not such as to provide 40 for quick changes in the position of the yarn feeders but such quick changes are necessary if narrow stripes are to be produced. I therefore provide the machine with means whereby the desired quick changes in the position of the yarn feeders can be effected independently of any change in their position

which may be due to the action of the ordinary pattern mechanism of the machine, the latter, if used at all, being employed only when broader stripes are to be produced.

In carrying out my invention I provide 45 connections 5, 5^a between the levers 3, 3^a and other levers 6, 6^a, pivoted in a structure 7 located at one side of that carrying the yarn feeders and their operating levers, this structure also providing for the support of 50 a shaft 8 to which are secured a pair of pattern drums 9, 9^a, and a ratchet wheel 10, the latter being engaged by a pawl 11 pivoted at the outer end of an arm 12 which is mounted 55 so as to swing upon the shaft 8 and is 60 vibrated, through the medium of a link connection 13, by a vertically reciprocating bar 14, the latter, being suitably guided on the frame of the machine and normally depressed by means of a spring 14^a. 65

The levers 3, 3^a can either be actuated by the main pattern device through the connections 4, 4^a, or by the supplementary pattern device through the medium of the levers 6, 6^a and connections 5, 5^a, it being understood, 70 of course, that the pattern drum which controls the connections 4, 4^a releases the same when the supplementary pattern device starts to act, and resumes control of the same 75 when said supplementary pattern device ceases to act.

Mounted in bearings adjacent to the lower end of the bar 14 is a rock shaft 15 which carries an arm 16, and upon the latter is pivotally mounted a toe 17 normally held in 80 operative position by means of a spring 18. Constant rocking movement is imparted to the shaft 15 by any suitable means, the arm 16 being, therefore, constantly vibrated so that as long as the bar 14 is in the path of movement of the toe 17 it will, on each vibration of the arm 16, be lifted by said toe and then permitted to drop on the backward swing of the arm, each lift of the bar 14 being accompanied by a forward movement of the 85 ratchet wheel 10 to the extent of one tooth and a like forward movement of each of the pattern drums 9 and 9^a. 100

The spring 14^a besides imparting downward movement to the bar 14 also tends to draw the same laterally out of the path of movement of the toe 17 but the bar 14 is under control of a pattern chain, drum, wheel, or other device 19, which acts upon a lever 20 pivotally mounted on the frame of 110

the machine and connected by a link 21 to a bell crank lever 22, likewise pivoted on the frame of the machine and carrying an anti-friction roller 23 which bears against the back of the bar 14, as shown in Fig. 1.

Some of the links of the pattern chain have lugs 19^a and when the lever 20 is acted upon by one of said lugs the lower end of the bar 14 will be pushed inwardly in the 10 path of the swinging toe 17 and the bar 14 will be reciprocated once for each vibration of the arm 16 as long as it remains in this position, the withdrawal of the lug 19^a from the lever 20 permitting the bar 14 to swing 15 outwardly away from the path of the swinging toe 17 and thereby arresting the reciprocating movements of said bar 14.

If the bar 14 happens to be projected while the arm 16 is in its uppermost position, the 20 contact of the toe 17 with the bar 14, on the downward swing of the arm, will cause said toe to yield until it has been carried below the end of the bar, whereupon it will at once swing forward again, so as to engage the 25 bar on its next upward movement.

The pattern drum 9 has alternate high members *x* and low members *y* and the pattern drum 9^a has like high members *x'* and 30 alternating low members, the high members of one drum being in line laterally with the low members of the adjoining drum.

The levers 6 and 6^a have projecting teeth 25 and 25^a for the action, respectively, of the drums 9 and 9^a, consequently when a lever 6 35 is depressed by the action of the drum 9 so as to raise the corresponding yarn feeder 1 out of feeding position the lever 6^a will be permitted to rise by the corresponding drum 9^a so as to permit the yarn feeder 1^a controlled thereby to drop into feeding position 40 and when the lever 6 rises the lever 6^a will at the same time be depressed, consequently there will be a change in the position of the yarn feeders 1 and 1^a for each intermittent 45 movement of the drums 9, 9^a, that is to say, for each forward movement of the ratchet wheel 10 to the extent of one tooth and each vertical reciprocation of the bar 14, hence, as long as the lower end of said bar is 50 held in position to engage with the swinging toe 17 there will be a change of feed for each vibration of the arm 16, but when the lower end of the bar 14 has been permitted to swing out of the path of movement of the 55 toe 17 the same yarn will be fed to the nee-

dles continuously until the bar 14 has again been placed under control of the vibrating arm 16 by the pattern device 19. It will be evident, therefore, that as long as the intermittent forward movements are being imparted to the drums 9 and 9^a quick changes in the positions of the yarn feeders 1 and 1^a will be effected and narrow stripes will be formed in the knitted web but when the movements of the drums 9 and 9^a are arrested 65 the same yarn will be fed to the needles during such period of rest and a stripe of any desired width can be produced.

If more than two yarn feeders are employed the number of pattern drums may be 70 correspondingly increased.

I claim:

1. The combination, in a knitting machine, of a plurality of yarn feeders each movable into and out of feeding position, controllers, 75 one for each of said yarn feeders, said controllers being such as to cause movement of one feeder out of feeding position as another feeder is moved into feeding position, and means for moving said controllers simultaneously, said means comprising a reciprocable bar, a vibrating actuator therefor, and means for moving said bar into and out of the path of said actuator, said means comprising a pattern chain, a lever acted on by 80 said chain, and a bell crank lever having one arm connected to said first-named lever and the other arm having a bearing on the reciprocable bar, in respect to which bearing the bar is free to slide.

2. The combination, in a knitting machine, of a plurality of yarn feeders each movable into and out of feeding position, controllers, one for each of said yarn feeders, said controllers being such as to cause movement of one feeder out of feeding position as another feeder is moved into feeding position, and means for moving said controllers simultaneously, said means comprising a reciprocable bar, a vibrating actuator 95 therefor, having a spring-pressed toe thereon, and means for moving said bar into and out of the path of movement of said toe.

In testimony whereof, I have signed my name to this specification, in the presence of 105 two subscribing witnesses.

RAYMOND FISHER.
